UNITED STATES PATENT OFFICE.

FREDERICK H. BEROLD, JR., OF CINCINNATI, OHIO.

PAPER-BAG MACHINE.

1,212,178.

Specification of Letters Patent.

Patented Jan. 16, 1917.

Application filed June 21, 1908, Serial No. 503,886. Renewed November 6, 1916. Serial No. 129,914.

To all whom it may concern:

Be it known that I, FREDERICK H. BEROLD, Jr., a citizen of the United States, residing in the city of Cincinnati, county of Hamilton, and State of Ohio, have invented a certain new and useful Paper-Bag Machine, of which the following is a full, clear, and exact description, reference being had to the accompanying drawings, forming part of this specification.

My invention embodies a completely organized machine for forming and simultaneously lining paper bags with suitable lining material, so that each bag as it is delivered from the machine is of the duplex type, a complete outer bag or envelop and a complete inner bag or lining member.

The machine is organized to receive webs of paper from suitable rolls, to properly paraffin or apply the water proofing material to the web from which the lining member is to be formed, to trim the duplicate webs to proper size, to print the desired advertising matter on the outer or envelop member, to cut and to form the blanks, to bring them together for folding, to apply the necessary glue or adhesive material, and to fold and deliver the completed bags printed and lined, with great rapidity from the machine, where they are automatically counted and arranged in piles or packs of the desired number of bags for each package.

The machine embodies a great variety of novel features of construction and operation which, in course of the accompanying description, will be fully pointed out and claimed in the claims.

In the drawings Figure 1 is a side elevation of my machine. Fig. 2 is a top plan view of the same. Fig. 3 is a front elevation of a pair of the rotary cutting dies. Fig. 4 is a side elevation of same. Fig. 5 is a plan view of a portion of the duplex webs of paper after the webs have passed the cutting dies. Fig. 6 is a detail side elevation of the printing cylinders for the outer envelop and the slitters for trimming the side edges of both webs, taken from the opposite side of the machine to that shown in Fig. 1. Fig. 7 is a front elevation of this same portion of the machine. Fig. 8 is a front elevation partly in section of the rotary die cutters, showing the receptacles for drawing off the surplus paper cut from the webs. Fig. 9 is a side elevation taken from the left hand side of the construction shown in Fig. 8.

Fig. 10 is a central vertical section of the same. Fig. 11 is a front elevation partly in section illustrating the carrying and severing cylinders. Fig. 12 is a side elevation of same. Fig. 13 is a side elevation of the glue applying and delivery mechanism. Fig. 14 is a front elevation of same.

1, 1, are the solid and substantial side frames suitably bolted and braced together to form a substantial framework for the operating parts of the machine, and provided at proper points with journal bearings for the large number of rotary parts, which bearings will not be specifically described, but which it will be understood are supplied as illustrated, for all of the rotating shafts and other rotary parts.

Mounted on suitable spindles journaled in the framework at the rear of the machine, are the paper rolls 2 and 3 from which the bags are formed. These rolls are provided with suitable adjustable tension devices 4, 5, for imparting the proper tension on the rolls in feeding the webs of paper therefrom. The web 6 from the roll 2 forms the outer envelop and the web 7 from the roll 3 supplies the material for the lining.

While paraffined or waxed paper is furnished as a commercial article in rolls, it has been found difficult to handle, in a paper bag machine, lining paper that has been previously paraffined, and I have, therefore, provided as one of the important parts of my machine, apparatus for paraffining the paper at the same time that it is fed to the machine, for cutting and folding, as the lining member of the duplex bag.

One difficulty arises in connection with passing the web of paper through a suitable paraffin bath to be fed continuously to the bag forming mechanism, and that is that the paraffin must be maintained at a constantly uniform temperature. As the paraffin is taken up from the trough by the paper, it is necessary to supply fresh water proofing material, and the addition of a fresh supply to the paraffin trough lowers the temperature, and at once difficulties arise with the paraffin web. Moreover as it is intended to superimpose the lining web upon the envelop web, in forming the bag it is essential that the web should be properly dried before it reaches the bag forming mechanism. To overcome these difficulties, I provide as follows: Located horizontally in the upper end of the rear portion of the frame is a trough

or receptacle 8 for the liquid paraffin, and in this trough is mounted the paraffin distributing roll 9, and immediately above it and bearing on its surface the pressure roll 10, and the web 7 from the roll 3 is fed over the guide roller 11 and between the rolls 9 and 10, where it receives its paraffin bath, the distributing roll 9 being driven by suitable sprockets and sprocket chains from the driving mechanism, and the distributing rolls also being provided with a scraper to scrape off the surplus paraffin. The trough is provided with a steam jacket with steam supply therefor, to maintain a uniform temperature for the paraffin in the trough. In order that this trough may be kept supplied with liquid paraffin at the proper temperature, I melt the paraffin in a separate receptacle, not shown, and run same to the trough through the pipe 12 provided with a proper non-conducting jacket 13, and with a steam pipe 14 passing through the paraffin pipe so that the paraffin as it is run from the tank, may be maintained at the uniform temperature required for the paper, and as an additional supply is required the heated paraffin is run into the trough through the delivery pipe 15 connected with the pipe 12, and controlled by a suitable valve. In this way the paraffined material may be maintained in the paraffin trough at a uniform temperature not affected by the change of temperature incident to supplying fresh paraffin which has to be dissolved and heated. The web 7 after it receives its paraffin bath passes over the guide roller 16 and around the steam drum 17 where the temperature is maintained to thoroughly saturate the paper, and thence it passes over the cooling drum 18, idler rolls being provided to give the necessary direction to the web.

Mounted in the side standards, a part of the main frame, are the draw rollers 19 and 20, through which the paraffined web is then passed, and which maintain the proper tension and draft on the web. Thence the web is passed between the slitting disks 21, 22, 23, 24 as shown in the upper portion of Fig. 7, where the side edges are trimmed off and the web cut of proper width. These slitters are of the ordinary construction of rotary slitting devices mounted respectively on shafts 25 and 26 driven by a suitable train of gearing, and the slitting disks are adjustable on these shafts for the varying widths required. As the web 7 is receiving its bath of paraffin and being dried and fed to the slitting disks, the web 6 from the roll 2 is fed over the guide rollers 27, 28 to the printing cylinders 29, 30. These printing cylinders are of the ordinary construction for a cylinder press and the forms on the cylinder 29 receive their ink from the inking receptacle 31, through the ordinary series of ink distributing rolls 32, which is not

necessary to describe in detail. It will also be understood that the cutting cylinders and inking rolls are rotated in the usual way by proper gearing connection with the main driving mechanism of the machine.

From the printing cylinder the web 6 is fed to a set of slitting disks 33, 34, 35 and 36 mounted on shafts 37, 38 in all respects similar to the upper set of slitting disks heretofore described for the lining, where the web for the envelop member is cut of the proper size. The lining web and the envelop web are thence fed to the rotary cutting dies which are arranged in pairs one above the other in suitable standards on the framework, and the blanks cut into proper shape for folding into the desired bags. One pair of these disks is illustrated in detail in Figs. 3 and 4. Each pair of these disks 39, 40, is provided with a hub portion 41, 42, mounted on the shafts 43, 44, and secured by set screws so that they can be adjusted, for proper sizes on the shafts, and so that the disks can be removed from the shafts and other disks substituted to cut out different blanks. The lower disks of each pair carry fixed cutting blades 45, 46 set in suitable annular grooves in the periphery of the disk, and with a transverse portion 47, while the upper set of coöperating disks 48, 49, carries a similar cutting blade 48, 49, which blade is arranged to be adjustable in the slot by the set screws 50, so that the two coöperating cutting blades will give a proper shearing cut. The paper web for the lining and for the envelop member being passed through their respective rotary cutters, the blanks are cut away as illustrated in Fig. 5 at 51, 51 for the lining member and 52, 52 for the envelop member. The portion of the web 53 for the lining member and 54 for the envelop member forming one side of the flat bag, and the portion 55 for the lining member and 56 for the envelop member forming the other side of the bag, and the blanks being ultimately folded on the transverse lines 57 and 58 to form the bottom line of fold for the bags, while the blanks are ultimately severed on the dotted lines 59 and 60 for the upper opening edge of the bag.

In order to remove the surplus material cut out by the rotary dies, I provide the receptacles 61 and 62 for each set of rotary dies, the receptacles being preferably of sheet metal open at the top, and surrounding the lower set of cutting disks in each case. These receptacles are provided with the chutes 63, 64 which are connected with a suction blower not shown, and the strips of paper as they are cut from the blanks are drawn down through the receptacles and chutes and disposed of. Having passed the cutting dies, the two webs are brought together around the guide roller 65 with the

broad side 53 of the lining blank superimposed on the broad side 54 of the envelop blank with the bottom line of fold 57 and 58 coinciding, and the narrow side 55 of the lining blank superimposed on the narrow side 56 of the envelop blank. The two webs thus superimposed are then passed over the plate 66 the side edges of which are provided with inwardly curved flanges 67, 67, 6 where the side edges of the two blanks are turned over on the lines 68, 68 for the lining and 69, 69 for the envelop member. Inasmuch as the lining web is wider than the envelop web for the bottom sides of the two 10 blanks, the narrow flaps 70 for the outer blank and wide flaps 71, 71 will be formed for the lining blank which will extend inwardly beyond the narrow side flaps of the envelop blank. The webs are then fed to the 15 carrying cylinder 72, which is mounted in suitable journals in the frame and suitably driven by a train of gearing from the driving shaft. This cylinder is provided with the slotted plates 73, 73 running lengthwise of the cylinder, and arranged on opposite sides of the periphery, the longitudinal slot 74 being formed therein to receive the cutting knife for severing the bag when folded from the web. Also mounted lengthwise on this carrying cylinder, at points 90 degrees from the cutting blades are the gripping bars 74', 74'. One member of this gripping means is a fixed plate 75 mounted lengthwise in a suitable cut-away portion of 20 the cylinder, and the other member of the grippers is a movable plate 76 which is carried on side plates 77 which plates are curved segmentally and mounted on the ends of the carrying cylinder.

40 78 is a rock shaft one for each pair of grippers, mounted in the cylinder and carrying a short arm 84 and a longer arm 79, these arms being secured to the shaft 78 by the set screws 85, 86. The short arm 84 is 45 pivoted by the screw 87 to the side plate of the movable gripper, and the long arm 79 carries a roller 80 on its outer end which roller bears upon the cam 81 fixed on the frame, and this cam is provided with the 50 cam surface 82, as indicated by dotted lines in Fig. 12. The outer end of the side plate 77 is connected by a coiled spring 83 to a pin fixed on the cylinder.

It will be understood that the arms 77 which carry the movable gripper plate are duplex for each end of the cylinder, and that the above description of the construction applies to both ends of the cylinder.

The tendency of the coiled springs 83 will 60 be to close the gripping plates, but so long as the roller 80 rides on the high surface of the cam 81 the arm 79 and the rock shaft 78 with its connecting arm 84 will push the movable plate away from the fixed gripper plate, and the grippers will be opened. As

the roller 80 rides down to the low surface of the cam the tension of the coiled spring 83 will close the gripper plate. The cam surface on the cam is so formed that each pair of grippers will be held closed a little 70 more than one-third of the revolution of the carrying wheel. The function of these gripper plates is to hold the paper blank on the carrying wheel, creasing it at the bottom line of fold until the duplex bag is supplied 75 with the necessary adhesive material, and properly folded and cut from the web to be delivered from the machine.

In order to force the bottom line of folds between the gripper plates and also to sever 80 the bag from the web, I provide the cylinder 88, mounted by bolts 89 in the slot 90 in the shaft 91 journaled in suitable journals in the framework, and held with proper tension on the carrying roll by the coiled springs 92, 92. 85

Mounted in suitable slots or cut-away portions of the cylinder 88 on opposite sides are the bars 93, 94. These bars are provided with transverse arms 95, 96 at each end coupled together by the coiled springs 97, 97 90 and 98, 98. The bar 93 carries a serrated cutting knife 99, and the bar 94 carries the plate 100. The outer ends of the bar 93 carrying the cutting knife is provided with the roller 101, and the outer end of the bar 94 95 carries at each end a block 102 which is provided with a beveled surface 103. Fixed on the framework at each end of the bars 93 and 94 is a disk 104 which has a beveled lug 105 fixed in its surface. As the beveled surface 103 of the block 102 comes in contact with this lug, the plate 100 mounted on the bar 94, which normally is held flush with the surface of the cylinder will be projected therefrom to enter in between the open jaws of the gripper, and this will force the web of paper in between the gripping plates, the cam 81 being so arranged that the grippers will then close, holding the web on its folding line to the carrying wheel. As soon as the bar 94 has passed the lug 105, the coiled springs will retract the folding plate 100 flush with the surface of the cylinder 88. As the two cylinders are rotated in the direction of the arrows by suitable gearing from the driving mechanism, when the cutter bar 93 carrying the cutting knife 99 reaches the beveled lug 105, the roller 101 110 will project the cutting knife from the surface of the upper cylinder into the slot 74 115 in the plate 73, and the paper web will be severed.

In order not to finally release the bag from the carrying wheel, both cylinders are provided with peripheral grooves 106, 107 115 so that the bag will not be completely severed.

As soon as the blank has been grasped by the grippers and it is held on the carrying wheel, the necessary adhesive material is ap- 130

plied to the side edges of the blank. This is accomplished by the apparatus shown in Figs. 13 and 14.

108 is a suitable pan or receptacle for containing the glue mounted in the framework, and in this receptacle is journaled a roller 109 which roller contacts with another roller 110 suitably journaled in the framework. 111 is a shaft also suitably journaled in the framework, which carries adjustably mounted thereon a pair of segmental daubers 112, 112 which contact with the glue roller 110 to receive the necessary glue and convey it to the side edges of the blank. The roller 109 is driven by the gear 113 which receives its motion from a screw 114 driven by a train of beveled gears and pinions from the driving mechanism, while the roller 110 and shaft 111 receive their motion from another 20 and separate train of gearing from the driving mechanism.

It is usual in glue applying devices to provide a roller which runs in the receptacle for the glue and supplies the glue for the 25 daubers, and to provide in connection therewith a scraping plate to scrape the excess of glue from the glue delivering roll. With this construction dirt accumulates underneath the plate, and soon stops the proper 30 supply and distribution of the glue. In order to overcome this difficulty, I abandoned the use of the scraping plate and substituted the roll 109 therefor. This roll running in contact with the glue distributing roll 110 allows any particles of dirt to pass on to the distributing roll and this dirt does no particular harm, while the close contact of the rollers 109 and 110 prevents any 35 excess of glue accumulating on the distributing roll 110. After the glue is supplied to the side edges of the web of paper, the forward edge of the blank is completely severed from the web so as to loosen the forward flap of the blank and allow it to be folded 40 down over the glued portion by an automatic blower.

The shaft of the carrying cylinder is hollow and provided with a pair of blowing tubes 115 as shown in Figs. 2 and 12, 50 the nozzles of which extend nearly to the surface of the carrying wheel underneath the paper web.

116 (Fig. 1) is a pump driven by suitable pitmen and connections with the driving 55 mechanism. 117 is a pipe from this pump to the hollow carrying cylinder shaft, while the movements are so timed that at the proper moment a puff of air is driven through the nozzle 115 to tear the web at the points left by the grooves 106, 107, and the front edge of the blank is completely severed 60 from the web. This leaves the outer end of the blank free, and inasmuch as the bottom or folding edge of the blank is still held on the carrying wheel, the blank is carried

under the folding roller 118, and the duplex bag folded. In order that this folding may be insured, I provide a shaft 119 which carries disks or pins 120, and which shaft is rotated by suitable gearing in the same direction as the carrying wheel, so as to tend to throw out and away from the carrying wheel the loose flap of the paper blank. The bag having thus been completely formed, is fed down between the rolls 121, 122 to the delivery mechanism. This delivery mechanism comprises a table 123, which supports on each side a pair of vertical guides 124 between which the bag is delivered in upright position against a movable vertical plate 125, which plate is mounted in a slot in the table 123, so as to move outwardly as the bags accumulate. 126 is a pushing plate having a central stud 127 sliding in a suitable bearing 128 on the table frame, and as the bags are delivered between the vertical guides 124, the pushing plate 126 is moved forward by a common well known eccentric disk construction indicated at 129 in Fig. 13, which pushes the bag and the plate 125 forward, as the bags accumulate. In order to indicate when a certain number of bags, as fifty, have been delivered, I provide for a pushing plate which will contact with the side edges of the bags and push out of alignment every fiftieth bag. This construction consists of a lever 130 (Figs. 13 and 14), which lever is pivoted on the table frame 131, and carries at its upper end a thin push plate 132. The lower end of the lever 130 is connected by pin and slot connections 133 with the shaft 134 mounted transversely in suitable bearings underneath the table, and adapted to be shifted transversely to rock the lever 130 and cause the plate 132 to shove out of alignment one of the paper bags. The shaft 134 carries at one end the depending beveled lug 135. Mounted horizontally underneath the shaft 134 is a disk 136 which carries a pin 137, and this disk 136 is carried by the worm gear 138 which meshes with the worm 139 on a shaft 140 journaled in the framework, and rotated by a suitable sprocket chain gear from the driving mechanism. The parts are so arranged that as each bag is delivered, the worm gear 138 will be moved one tooth, and for every fifty bags delivered, the worm gear and disk plate 136 will be given a complete rotation, which rotation will bring the pin 137 into contact with the beveled lug 135 on the shaft 134, and shift the lever 130 to throw a bag out of alignment. A coiled spring 141 bearing between the head of the shaft and the lug on the frame, turns the shaft 134 to its normal position as soon as it has been shifted. In this way the operator can remove from the receiving tray fifty bags at a time, without the necessity of counting them.

The operation of the entire machine as a whole will be evident from the foregoing description of the several parts. In describing the various mechanisms, no attempt has been made to specifically point out by number and letter, the various trains of gearing by which the large number of rotating shafts are operated as this will apparently needlessly encumber the description. It will be understood that chain gearing, beveled gears and spur gears and pinions are provided properly arranged and timed to impart the proper timed movements to the rotating parts. The main driving shaft of the machine is a shaft 150 with fly-wheel 151, and carrying loose and tight pulleys 152, with the belt shifter 153 operated by suitable hand lever.

The machine is as described designed for forming from suitable webs of paper, lined paper bags of the duplex type provided with side seams. It will be understood, however, that other constructions of flat paper bags may be readily formed, in which one or both of the duplex parts of the bag may have a central seam.

The general plan of the construction which forms the essential features of my invention, do not, of course, relate to the various details which I have only described in general terms.

The most important objects of my invention are to provide a construction in which the web to form the lining of the bag can be effectively coated or saturated with any material desired during the continuous operation of the machine, and in which the lining member can be continuously superimposed on the envelop member after both webs have been properly cut, and in which the super-imposed webs are then folded and glued and separate duplex bags delivered continuously and with great rapidity from the machine.

Another important construction in my machine, relates to the glue applying devices whereby a rotating roll is substituted for the ordinary scraping plate so that there is no clogging of the glue. This is of importance inasmuch as the bags are finished and delivered with great rapidity, and any failure to properly apply the glue results in a large number of defective bags before the fault is noticed and the defect corrected. It is also of importance to construct the blank forming dies so that they can be readily strung on the proper shaft, adjusted for sizes and different dies substituted for the cutting of different characters of blanks.

Having thus described my invention what I claim as new and desire to secure by Letters Patent, is:

1. In a paper bag machine, feeding mechanism for feeding two separate webs of paper, two cutting mechanisms for sepa-

rately cutting the webs to form bag blanks, a former for partially folding the blanks when superimposed, a carrying cylinder, with means for grasping and holding thereon the superimposed blanks, and for folding same simultaneously into complete bags. 70

2. In a paper bag machine, feeding mechanism for feeding two separate webs of paper, two cutting mechanisms for separately cutting the webs to form bag blanks, a former for folding the sides of the blanks when superimposed, a rotatable carrying cylinder and a gripping means to hold the duplex blank thereon, comprising a fixed and a movable bar mounted lengthwise of the cylinder, with side arms and springs secured thereto to close said gripping means, with cams to operate said grippers during a portion of the rotation of said cylinder. 75

3. In a paper bag machine, feeding mechanism for feeding two separate webs of paper, two cutting mechanisms for separately cutting the webs to form bag blanks, a single former for folding the sides of the blanks when superimposed, a rotatable carrying cylinder and a gripping means to hold the duplex blank thereon, comprising a fixed and a movable bar mounted lengthwise of the cylinder, with means for opening and means for closing said movable bar at stated 90 intervals during the rotation of the cylinder. 95

4. In a paper bag machine, feeding mechanism for feeding two separate webs of paper, two cutting mechanisms for separately cutting the webs to form bag blanks, a single former for folding the sides of the blanks when superimposed, a carrying cylinder with means for grasping and holding thereon the superimposed blanks, means for distributing glue to both of said blanks 100 simultaneously, and mechanism for folding same into a duplex bag in one operation. 105

5. In a paper bag machine, feeding mechanism for feeding two separate webs of paper, two cutting mechanisms for separately cutting the webs to form bag blanks, means for superimposing said two webs with fold lines of the blanks coinciding, and mechanism for grasping and holding said blanks and for folding both blanks simultaneously into complete bags. 110 115

6. In a paper bag machine, feeding mechanism for feeding two separate webs of paper, two cutting mechanisms for separately cutting the webs to form bag blanks, 120 means for superimposing said two webs, with the fold lines of the blanks coinciding, and mechanism for grasping and holding said blanks, means for applying glue to both blanks and for folding same into complete 125 bags.

7. In a paper bag machine, feeding mechanism for feeding two separate webs of paper, two cutting mechanisms for separately cutting the webs to form bag blanks, 130

- means for superimposing said two webs, with the fold lines of the blanks coinciding, and mechanism for grasping and holding said blanks, means for applying glue to both 5 blanks simultaneously and for folding same into complete bags, with mechanism for delivering the complete bags and for indicating packages of any desired number thereof.
8. In a paper bag machine, feeding 10 mechanism for feeding two separate webs of paper, two cutting mechanisms for separately cutting the webs to form bag blanks,

one cutting mechanism located above the other, with a paper receptacle and chute intermediate the two cutting mechanisms to 15 carry off the paper cuttings from the uppermost web to prevent lodging upon the undermost web and means for superimposing one web upon the other to form the duplex bag.
